Frederick John Osmond,

UNITED STATES PATENT OFFICE.

FREDERICK JOHN OSMOND, OF MOSELEY, ENGLAND.

DRIVING MECHANISM FOR BICYCLES.

SPECIFICATION forming part of Letters Patent No. 580,291, dated April 6, 1897.

Application filed December 1, 1896. Serial No. 614,092. (No model.) Patented in England May 11, 1895, No. 9,389.

To all whom it may concern:

Be it known that I, FREDERICK JOHN OSMOND, a subject of the Queen of Great Britain, residing at Moseley, England, have invented 5 certain new and useful Improvements in the Driving Mechanism of Bicycles, Tricycles, and other Velocipedes, (for which I have obtained Letters Patent of Great Britain, No. 9,389, dated May 11, 1895;) and I do hereby 10 declare that the following is a full, clear, and exact description of the invention, which will enable others skilled in the art to which it appertains to make and use the same.

My invention has reference to such driving 15 mechanism for bicycles, tricycles, and other velocipedes as consists of an interchangeable driving-chain ring secured to the ends of radial carrying-arms keyed on the crank-shaft; and my said invention consists of the improvements hereinafter described in connecting the said carrying-arms to the interchangeable driving-chain ring.

By my invention a very efficient connection 20 of the parts of this kind of driving mechanism is obtained, and the detachment of the said parts when necessary is readily effected.

My invention also permits of the use of unhardened interchangeable driving-chain rings with hardened radial carrying-arms.

According to my invention I make the driving-chain ring of such a sectional figure 25 that one face of the said ring near its inner edge is provided with a projecting rib, equidistant gaps or openings being left in the said rib for the outer ends of the radial connecting-arms on the crank-axle to fit closely in. The ends of the gaps or cut-away parts in the rib of the chain-ring form shoulders or abutments for the edges of the radial arms fitted 30 in the said gaps to bear against. The bottoms of the gaps or cut-away parts of the chain-ring rib are level with the face of the said ring, so that when the radial arms are introduced into the said gaps the parts of the 35 arms extending beyond the said gaps bear against the flat face of the ring.

The inner edge of the chain-ring and its rib may be made slightly conical, and each of the radial arms has a shoulder the outer face 40 of which may also be slightly conical, which shoulder on the arm when the latter is passed into the gap in the rib of the chain-ring seats

itself against the inner edge and rib of the chain-ring.

The conical seatings or abutting parts of the shoulder and ring are ground, so that a very accurate fitting of the parts is secured. After the radial connecting-arms on the crank-axle have been fitted in their respective gaps in the chain-rings each of the said arms is held or 55 bound in its place by a screw-pin passed from the unribbed side of the chain-ring through a large hole or clearance in the said ring and screwed into the extreme end of the arm. By thus connecting the radial arms on the crank- 60 axle to the driving-chain ring the thrust of the said arms upon the said ring is borne only at the shoulders or abutments formed by the ends of the gaps in the rib of the chain-ring, there being no strain upon the chain-ring at 65 the holding or binding screw-pins at the extreme ends of the arms in consequence of the size of the holes or clearances in the said ring through which the said screw-pins pass.

Figure 1 of the accompanying drawings represents an elevation of the inner side of a driving-chain ring and combined crank and chain-ring-carrying arms constructed and connected together according to my invention. Fig. 2 represents a vertical section of the same, 70 taken on the line xx , Fig. 1. Fig. 3 represents an elevation of the outer side of a portion of the chain-ring and one of the carrying-arms of the same. Fig. 4 is a section on the dotted line yy , Fig. 3. Figs. 5, 6, 7, and 8 represent the chain-ring and combined crank and 75 radial chain-ring-carrying arms detached.

The same letters of reference indicate the same parts in the several figures of the drawings.

In constructing interchangeable driving-chain rings according to my invention I form on the outer face of each of the said rings a projecting annular rib or flange a , provided at the parts where the chain-ring-carrying 80 arms b are to be connected to it with gaps or unflanged parts a^2 a^3 a^4 , in which gaps the ends of the said radial chain-ring-carrying arms b accurately fit, the edges of the arms when driving bearing against one or other of the shoulders or abutments a^5 a^6 at either side of the gaps a^2 .

The radial chain-ring-carrying arms b are provided with curved shoulders b^2 for tak-

ing a bearing against the inner side or edge of the driving-chain ring, (see Figs. 2, 3, and 4,) and thereby obtaining perfect concentricity in the fixing of the said ring to the 5 radial arms. Where thought necessary or desirable, the inner edge of the chain-ring may be made slightly conical, the outer or bearing sides of the curved shoulders b^2 having a corresponding figure, the inner edge of the ring 10 and the bearing side of the shoulders b^2 being ground so as to accurately fit one another.

When the interchangeable driving-chain ring is applied to the radial chain-ring-carrying arms b , screw-pins $c c c$ are passed through 15 holes $a^4 a^4 a^4$ in the face of the wheel into screwed holes $b^3 b^3 b^3$ in the ends of the radial chain-ring-carrying arms b . It will be seen by an examination of Figs. 2 and 4 that the holes $a^4 a^4 a^4$ in the chain-ring are of a 20 larger diameter than the stems of the screw-pins $c c c$, so that on the driving of the chain-ring no shearing strain is put on the connecting screw-pins $c c c$, the pressure of the radial chain-ring-carrying arms b being borne solely 25 by the shoulders or abutments $a^3 a^3$ of the rib or flange a , formed by the gaps $a^2 a^2 a^2$ in the said rib or flange a .

The bush of the combined crank and radial chain-ring-carrying arms is connected to 30 the crank-axle in the ordinary way.

Although I have shown my invention in

connection with a combined crank and radial chain-ring-carrying arms, yet I wish it to be understood that it is equally applicable to radial chain-ring-carrying arms which are 35 formed separate from the crank and are keyed independently to the crank-axle.

Having now particularly described and ascertained the nature of my invention and in what manner the same is to be performed, I 40 declare that I claim as my invention of improvements in the driving mechanism of bicycles, tricycles, and other velocipedes—

Interchangeable driving-chain rings having a rib or flange a on one side and gaps or 45 spaces a^2, a^2, a^2 in the said rib or flange a for the radial chain-ring-carrying arms b, b, b , keyed to the crank-axle to take in and fit, the said arms b, b, b having shoulders b^2, b^2, b^2 for engaging under and fitting the inner 50 side or edge of the chain-ring, the driving-chain ring being connected to the radial chain-ring-carrying arms by screw-pins c, c, c passing through large holes a^4, a^4, a^4 in the chain-ring and taking in screwed holes b^3, b^3, b^3 in the ends of the radial chain-ring-carrying arms b, b, b substantially as and for the purpose herein set forth and shown.

FREDERICK JOHN OSMOND. [L. S.]
